United States Patent Office.

CHARLES L. SNYDER, OF HARDIN, ILLINOIS.

Letters Patent No. 70,280, dated October 29, 1867.

IMPROVEMENT IN THRESHING MACHINES.

The Schedule referred to in these Letters Patent and making part of the same.

TO ALL WHOM IT MAY CONCERN:

Be it known that I, C. L. SNYDER, of Hardin, in the county of Calhoun, and State of Illinois, have made certain new and useful Improvements in Threshing Machines; and do hereby declare that the following is a full and clear description thereof, reference being had to the accompanying drawings, and to the letters of reference marked thereon.

This invention relates firstly to the arrangement of the gearing and operative parts of the machine, secondly to the construction of the feed-board, and thirdly to the straw-beater and conveyer.

To enable those skilled in the art to make and use my improved threshing machine, I will proceed to describe its construction and operation.

Figure 1 of the drawings is a side elevation of one of the improved threshers.

Figure 2 is a top plan of the same, and

Figure 3 is a longitudinal sectional elevation.

The frame A, the casing or housing A¹, and the wheels A², are constructed and employed in the usual manner, and need no minute description. The power, from whatever source derived, is transmitted by means of a belt to the driving or cylinder-shaft B, and is communicated from thence to the other parts of the machine. The thresher or cylinder B' is placed upon the shaft B, and operates in the usual manner upon the grain fed into it. The cog-wheel b, on the outer end of the shaft B, gears into the wheel c upon the shaft C, and the wheel c gears into the counter-wheel d upon the fan or blower-shaft D. Each of the wheels b c d is of such a size as to give the required motion to the operative parts with which they are connected. On the opposite end of the blower-shaft D from the wheel d is an endless screw, d', which gears into a pinion on the forward end of the shaft E, and a crank and pitman attached to the back end of the shaft transmit the required reciprocating motion to the zigzag or separator F. The blower d² is arranged to blow directly through the separator F and force the light chaff and dust out at the aperture f, while the good grain falls down through the spout f'. A new feature is introduced into the construction of the straw-conveyer C' by the introduction of a central drum or beater, c'. The action of this beater, which is composed of transverse slats affixed to two heads, is to strike the conveyer with its slats as it revolves, and so shake out all of the grain that may be clinging to the straw. The feed-board G is constructed so that it may be slipped out or in its place on the machine, when required, by having tenons g on its forward end which fit into sockets in the frame A prepared to receive them.

Having described my invention, what I claim, is—

1. I claim arrangement and employment of the endless screw d', in combination with the shaft E and zig-zag or separator F, as and for the purpose shown and described.
2. I claim the construction and arrangement of the feed-board G when applied to the frame A, as herein set forth.

In testimony of which invention I hereunto set my hand in presence of—
